Attorney

UNITED STATES PATENT OFFICE.

ERNEST L. PEITZ, OF RAPID CITY, SOUTH DAKOTA.

WIRE STRETCHER.

Application filed January 16, 1926. Serial No. 81,804.

The present invention relates to improvements in wire stretchers and has for its principal object to provide a simple and efficient device for stretching the broken ends 5 of a strand of fence wire whereby said ends may be spliced together.

One of the important objects of the present invention is to provide a wire stretcher wherein the same includes a means for 10 holding the wire taut in order to enable the adjacent ends of the strand to be spliced.

A further object is to provide a wire stretcher which is simple in construction, inexpensive, strong and durable and further well adapted to the purpose for which 15 it is designed.

Other objects and advantages of the invention will become apparent during the course of the following description taken in 20 connection with the accompanying drawing.

In the accompanying drawing forming a part of this application and in which like numerals designate like parts throughout the same:

25 Figure 1 is a side elevation of the wire stretcher embodying my invention, showing the position of the levers during the act of the stretching of the broken ends of the strand of wire.

30 Figure 2 is a side elevation showing the position of the parts after the wire has been stretched, and prior to the adjacent ends being spliced, and

35 Figure 3 is a detail perspective view of the tool.

In the drawing wherein for the purpose of illustration is shown the preferred embodiment of my invention, the numeral 1 designates the arm 1, the same being formed 40 of an elongated piece of flat metal, and being provided in its intermediate portion with the arched portion 2, the purpose of which will hereinafter be more fully described.

45 A fence wire gripping means is adapted to be attached to the outer end of the arm, the same including a block 3 which has its upper portion secured to one side face of the outer end of the arm, a pivoted cam 4 being supported on the depending portion 50 of the block and being adapted to coact with the bottom edge of the outer end of the arm for gripping and securing one end portion of the broken fence wire in the manner as clearly illustrated in Figure 1.

Cooperating with the arm 1 is the elongated

lever designated generally by the numeral 5, the same comprising a pair of elongated flat strips of metal designated by the numerals 6 and 7 respectively, the same 60 being arranged in spaced relation with respect to each other through the medium of a block 8 which has its upper portion secured between the outer ends of the strips 6 and 7, the lower portion of the block supporting a cam 9, similar to the cam 4 which is adapted for cooperation with the bottom edge of the strip 6 in clamping the other broken ends of the fence wire A as clearly shown in the drawing. A hook 10 is 70 pivotally supported between the inner ends of the strips 6 and 7 of the lever 5 on the pin 11 which extends transversely through the strips and the purpose of the hook will be hereinafter more fully described. 75

The inner end of the arm 1 is pivotally secured between the spaced strips 6 and 7 comprising the lever 5, at a point adjacent the outer end of said lever as indicated at 12. The pivot pin 12 is preferably arranged inwardly from the end of the lever 5 so that when the lever 1 is swung upwardly on its pivot 12, the inner end portion of the arm 1 will be adapted to be disposed in a horizontal plane between the strips 6 and 7 80 of the lever 5 when the latter is disposed in a horizontal plane in the manner more clearly shown in Figure 2. It is of course to be understood that the space between the strips 6 and 7 of the lever 5 is sufficient to 85 permit the lever to swing freely over the crown or arched portion 2 of said arm.

In use, one of the broken ends of the strand of wire A is clamped to the arm 1 by means of the wire gripping means provided at the outer end of the arm and this portion of the wire is so clamped as to have the free end thereof extending into the arched portion of the arm. The other end of the fence wire is clamped to the outer 100 end of the lever 5, as clearly shown in Figure 1. The longer end of the lever is then swung upwardly in the direction of the arrow, simultaneously causing the ends of the wire to be stretched, and when the lever is disposed in a horizontal position, the outer end thereof will have moved into the crown or arched portion 2 of the arm so that the free end of the wire which is clamped by the outer end of the lever will be disposed 105 in close proximity to the adjacent end of the wire. For the purpose of holding the parts 110

in this position so that the wire is held taut, the hook 10 is engaged with one of the barbs of the wire as illustrated in Figure 2. If the wire is not provided with barbs, the portion of the wire adjacent the hook is twisted therearound. The operator is then free to use both of his hands in splicing the adjacent ends of the broken wire, and the arched portion enables the operator to easily grasp the adjacent ends of the wire to facilitate the twisting or splicing thereof.

In order that the wire stretcher may be used in stretching a broken fence wire at a corner post there is provided a post encircling chain 13, one end thereof being connected to the outer end of the arm 1 through the medium of a swivel connection 14, the other end having a hook 15 carried thereby which engages a suitable eye 16 supported on the top of the outer end portion of the arm after the chain has been placed around the post.

The provision of a wire stretcher of the above mentioned character will enable the broken ends of a wire to be readily and easily stretched and spliced, and there will be no possibility of any slack occurring in the wire while the broken ends thereof are being spliced. The simplicity in which my device is constructed enables the same to be readily and easily operated, and will at all times be positive and efficient in carrying out the purposes for which it is designed.

While I have shown the preferred embodiment of my invention, it is to be understood that minor changes in the size, shape and arrangement of parts may be resorted to

without departing from the spirit of the invention and the scope of the appended claim.

Having thus described the invention, what I claim as new is:—

A wire stretcher comprising an arm, the intermediate portion thereof being arched, wire gripping means carried by the outer end of said arm, a lever comprising a pair of parallel spaced flat strips, a block secured between the outer ends of said strips, wire gripping means associated with said block, a hook pivotally secured between the inner ends of said strips, the inner end of said arm being pivotally secured between the spaced strips of the lever at a point adjacent the outer end thereof, the inner end portion of said arm being adapted to be confined between the spaced outer end portions of the strips of the lever when the latter is swung to a horizontal position, whereby the ends of the broken fence wire are disposed within the arched portion of the arm, the wire gripping means carried by the outer end of lever being also disposed within the arched portion of the arm when the lever is swung to a horizontal position in one direction, the hook secured between the inner ends of the strips of the lever being adapted for engagement with the portion of the wire adjacent the inner end of the lever when the latter has been swung to its horizontal position whereby the wire will be held taut.

In testimony whereof I affix my signature.

ERNEST L. PEITZ.
